UNITED STATES PATENT OFFICE.

FERDINAND LOGAN, OF PHOENIXVILLE, PENNSYLVANIA.

PROCESS OF PRODUCING COKE AND GAS.

No. 833,471.

Specification of Letters Patent.

Patented Oct. 16, 1906.

Original application filed May 20, 1902, Serial No. 108,228. Divided and this application filed August 25, 1904. Serial No. 222,172.

To all whom it may concern:

Be it known that I, FERDINAND LOGAN, a citizen of the United States, residing at Phoenixville, in the county of Chester and State of Pennsylvania, have invented new and useful Improvements in Processes for the Production of Coke and Gas from Coke-Ovens, of which the following is a specification.

My invention relates to processes for the production and utilization of gas from coke-ovens; and one of the objects of the same is to provide an economical and continuous process for producing coke and saving the resultant gases.

Another object is to provide a process which can be continuously carried out and which will be economical and which will utilize all the desirable qualities of the materials used in making coke and gas and at the same time will result in the production of a high-grade coke, saving the resultant gases, and enriching, fixing, and storing such gases for subsequent use for heating and lighting purposes.

The process hereinafter set forth is a division of a copending application filed by me under date of May 20, 1902, bearing Serial No. 108,228, and in carrying out my process I make use of the apparatus described and claimed in the application aforesaid, which is illustrated in the accompanying drawings, in which—

Figure 1 is a front elevation of a pair of connected coke-ovens designed to carry out my process. Fig. 2 is a vertical central longitudinal section of the same looking from the rear side of the ovens. Fig. 3 is a plan view of the same.

In the drawings I have illustrated a pair of ovens properly connected by piping; but it will be understood that my invention contemplates the use of a series of such ovens connected by pipes provided with valves and cocks in order that communication may be established between any two or more of the ovens in the series for purposes which will hereinafter appear.

In said drawings the numerals 1 2 designate two ovens of the ordinary beehive type. These ovens are substantially identical in construction and are counterparts of the other groups of ovens in the series to be used. Hence a description of one pair will serve as a description for all. Each of these ovens consists of a metallic dome or jacket 3, lined with mineral wool or other suitable non-con-

ducting material 4 and having an inner layer of fire-brick 5, while the outer side of the dome 3 is provided with a packing 6, of mineral wool or like material, and an outer covering of masonry-work 7. The ovens are supported upon a solid base 8, and each oven is provided at the top with a charging-eye 9, an interior coking-chamber 10, and a door 11 to permit the removal of the coke. The bottom 12 of the coking-chamber 10 is formed of fire-brick or other suitable material, and a number of perforations 13 are formed in this bottom for a purpose which will be herein-after described.

A steam-boiler of suitable dimensions and of ordinary construction is located at any convenient point near the ovens, and a steam-pipe 14 extends from the boiler along the front of the ovens, and said pipe is provided with stop-cocks 15, one between each pair of ovens in the plant. Branch pipes 16 extend from the steam-pipe 14 into and through the wall of each oven, said branch pipes terminating in the space between the base 8 and the perforated bottom 12 of the coking-chamber. An oil-supply pipe 17 extends from any suitable source of supply along in front of the ovens, and branch pipes 18 pass through the wall of each oven and communicate with the coking-chamber at a point above the charge. In order that the oil-supply may be cut off from any one of the ovens, each branch pipe 18 is provided with a suitable stop-cock *a*, Fig. 3, while stop-cocks *b* are provided in the branch pipes 16 to cut off the steam from any one or more of the ovens, as will be readily understood. Stop-cocks 19 are provided between each pair of ovens in the oil-supply pipe 17. At a point near the top of the oven a gas-pipe 20 connects the ovens and establishes communication between all of the ovens of the plant and the gasometer, a valve 21 being provided in said pipe between each pair of ovens. A pipe 22 establishes communication between the upper portions of the ovens and at an intermediate point is provided with a suitable blower 23 and a cock or valve 24.

The process to be carried out with this apparatus is as follows: The ovens are properly charged with bituminous coal, and the charge in one of each pair of ovens is ignited in any suitable manner, each oven being heated by the burning charge therein, the cocks and valves being closed to cut off all communication with the other ovens of the series. The

2

air necessary to support the combustion enters the door 11 and forms a natural draft from this door to the eye 9. When the coking operation has proceeded until about 5 half the time required for "coking off," the door 11 and the eye 9 are closed and the other ovens of the series are started in the same manner as oven 1. To define the process in connection with the two ovens shown, let it 10 be assumed that the charge in oven 1 has been heated for a certain time before heat is applied to oven 2, communication being cut off between the ovens. When oven 1 is in condition for coking off—that is to say, when the 15 charge has reached its highest incandescent temperature and is in condition to form coke—the coking operation has been going on in oven 2. The valve 21 is then opened to establish communication between the two ovens 20 and to permit the gas to flow to the gasometer through pipe 20. The valve 24 is also opened and the blower 23 is operated to force the gas from oven 2 into oven 1. The cock 15 in the steam-pipe is then opened and steam 25 is forced under the perforated bottom 12 in oven 1, the steam passing up into the incandescent coke, commingling with the gases conveyed from oven 2 and the gases driven off from the incandescent bed of coke, there- 30 by becoming thoroughly mixed and superheated in the upper portion of oven 1, the product thence being conveyed to the gasometer through pipe 20. At this time, if found necessary, the oil-cock 19 may be opened, and 35 a quantity of oil is thus mixed with the gas and steam to enrich the gas product. In the operation of the blower 23 and the valves 21 and 24, it will be understood that the blower may be reversed to serve either as a draft or a 40 suction device, and the valves may be either opened or closed, depending upon the direction which it is desired to force the gases. After the coke in oven 1 has become cool and has been removed therefrom the valves and 45 cocks are closed and the oven is recharged and ignited. When oven 2 is in condition for coking off and oven 1 has proceeded to a certain degree, then steam is admitted under the perforated bottom of oven 2 and 50 the cocks and valves opened to discharge the gas from oven 2 into oven 1, in the manner previously described. By way of example, I may operate as follows: Let it be assumed that after the oven 1 has been in operation 55 for about forty-eight hours, during which time the outlet at the top for the blast has been open and the charge is in a high state of incandescence, I am then ready to make gas and coke off—that is, cool off the incandes- 60 cent charge or body and drive off all the gases therefrom in order to produce the coke product, while oven 2 has been in operation for about twenty-four hours with the outlet for the blast open and is releasing certain gases. 65 The blast-openings in both ovens are now closed, and cock 21 may then be opened for about thirty minutes to permit the highly-heated gas from oven 1 to expand and pass into oven 2 or to permit the contents of the two ovens to commingle, thoroughly mix, superheat, and fix the gas. Valve 21 may then be closed, valve 24 opened, and the fan 23 operated to draw the commingled gas by suction from oven 2 to oven 1 and force it out through pipe 20 to the gasometer. Steam may then 70 be admitted under the grate-bars of oven 1 to drive off the gases from the incandescent charge to make water-gas and to cool the hot coke or coke off, and if it is desired to enrich the gas the oil-supply valves *a* are opened. 75 When the gas has been forced from oven 1 and the charge has become cool by the action of the steam and all the valves are closed, the coke product may be removed and the oven may be recharged and ignited. The time 80 consumed in the process of driving out the gas, cooling off, and removing the coke product and recharging the oven may be from thirty minutes to an hour, and hence if oven 2 is in condition for coking off in twenty-three 85 hours after oven 1 has been recharged and ignited then the gas from oven 2 is permitted to flow into oven 1 and is driven off to the gasometer by the fan in the same manner previously described. It will be understood, of 90 course, that the times necessary to reach the gas-making stage may vary considerably, depending upon the character of the coal used, the character of coke to be produced, and the kind of gas it may be desired to make. 95 The process may then be made continuous, as there will always be some ovens in the plant ready for coking off and each is connected up with another oven which is undergoing the coking process. The object of forcing 100 the gas as it arises from the oven which is ready for coking off into the oven which has not yet reached its highest temperature is to superheat and fix the entire product of the two ovens, and it has been found in practice 105 that this procedure insures a non-condensable gas product. Moreover, the commingling of the gases arising from two ovens under different degrees of heat saves certain gases which would otherwise go to waste through the outlet with the gaseous vapors from the oven of 110 lower temperature. 115

It will be understood that when the steam is projected under the perforated bottom of the oven at the time of coking off said oven 120 is closed to the outer air in order that all of the gaseous vapors remaining in the bed of coke may be driven therefrom into the upper portion of the oven and there allowed to thoroughly commingle and mix with the gas 125 from another oven and be superheated and conveyed to a gasometer, the latter being connected to each oven through the pipes 20 and said pipes having suitable branch pipes leading to the gasometer. This gasometer 130

may be located at any convenient point from which the gas may be led to the illuminating system, if desired. Each pair of ovens being connected by the controllable pipe or connection 22, the gas may pass (when the valve 24 is open) from one of the pair of ovens to the other, thereby permitting of the injecting of the gas from the coking-oven to the oven ready for coking off at the time when the formation of the water-gas is about to take place, thereby combining the results of both ovens, the valve 24 being closed excepting during this particular period. By injecting steam beneath a perforated bottom and in a closed oven the noxious gases also are removed from the coke-bed and are utilized as constituents in the final gas product. Moreover, the steam serves to cool the coke and does not cause it to disintegrate or break up into small particles as to materially reduce its value and cause more or less waste of the coke product.

What I desire to secure by Letters Patent and claim is—

1. The process of producing coke and gas, which consists in charging the oven with coal, heating the coal to incandescence, making water-gas by projecting a jet of steam under the charge in said oven when the charge has reached its highest incandescence or in condition for coking off, generating gas by distilling coal in another oven undergoing the coking operation, drawing the gas from this

oven, forcing it into the oven first named when making water-gas, combining the two gases, and leading the product to the gasometer.

2. The process of producing gas and coke, which consists in charging an oven with coal, heating the coal to incandescence, making water-gas by projecting steam under the charge in said oven when the charge has reached its highest incandescence or in condition for coking off, admitting oil to the oven above the charge, generating gas by distilling coal in another oven undergoing the coking operation, drawing the gas from this oven forcing it into the oven first named, combining the two gases, and leading the product to the gasometer.

3. The process of producing gas and coke, which consists in charging an oven with coal, heating the coal to incandescence, making water-gas by projecting steam under the charge in a closed oven, admitting oil above the charge, generating gas by distilling coal in another oven undergoing the coking operation, drawing the gas from this oven and intermittently forcing the gaseous product from said oven into the first-named, combining the two gases, and leading the resultant gas to a gasometer, substantially as described.
